UNITED STATES PATENT OFFICE.

ROGER L. NAY, OF MUSKOGEE, OKLAHOMA.

BOOKBINDER.

1,083,124.

Specification of Letters Patent. Patented Dec. 30, 1913.

Application filed February 7, 1913. Serial No. 746,905.

To all whom it may concern:

Be it known that I, ROGER L. NAY, a citizen of the United States, residing at Muskogee, in the county of Muskogee and

5 State of Oklahoma, have invented new and useful Improvements in Bookbinders, of which the following is a specification.

This invention relates to improvements in temporary binders and movable covers 10 for books, especially binders and covers for receipt, order check books, etc., which enable the stubs of checks or other forms to be removed and filed away for future use, after the checks or leaves in the book have 15 been used, one object of the invention being to provide improved means for detachably securing the binder to the cover, another object being to provide improved means for securing the stubs in the binder.

20 With the above and other objects in view, the invention consists in the construction, combination and arrangement of devices hereinafter described and claimed.

In the accompanying drawing:—Figure 25 1 is a longitudinal sectional view of a check book constructed in accordance with my invention, showing the same open. Fig. 2 is a transverse sectional view of the same on the plane indicated by the line $a-a$ of Fig. 1. Fig. 3 is a perspective view, showing the stubs and binder detached from the cover. Fig. 4 is a detail sectional view, partly 30 through the cover and partly through the binder, leaves or stubs, and a pair of the tubular binding members showing the binder with its leaves or stubs in the act of being detached from the cover. Figs. 5, 6 and 8 are perspective views of various forms 35 of books provided with my improved binders. Fig. 7 is a perspective view of the form of book shown in Fig. 1, provided with one of my improved binders and removed from the cover.

40 The cover of a check book or other book is indicated at 1, the flexible back being indicated at 2. In accordance with my invention, I provide a pair of suitable number of clasps 3 each of which comprises a base 4, and a stem 5 which projects centrally 45 from the base and has a rounded spring or solid clasp head 6. These clasps are arranged on the inner side of the cover at a point near the flexible back, the bases 3 of the clasps being embedded in the cover so 50 that the stems with their heads project inwardly from the cover. The leaves 7 which

may be checks or the leaves of any other book are gathered and their stub ends are placed in a binder 8. This binder is preferably made of leather but may be made of any other suitable material and comprises a back 9 together with a pair of spaced sides 10, the said sides being on opposite sides of the mass or body of checks or leaves of the book, the checks or leaves and also the sides of the binder being provided with registering openings 11. Through each of these openings 11 extends a pair of tubular binding members 12—13, the former being of slightly less diameter than the latter and being telescopically disposed therein. These tubular binding members are, respectively, provided with heads 14—15 at their outer ends, which heads bear on the outer sides of the sides 10 of the binder 8. The pairs of tubular binding members are arranged coincident with the clasps 3 when the binder with its checks or leaves is properly placed in the cover of the book and each of the larger tubular binding members 13 is provided at its outer end with a socket or flange 16 for the reception of the spring or solid head 6 of one of the clasps 3 so that the binder with its leaves or checks is securely but yet detachably held in place in 85 the cover by the coaction of the pairs of binding members 12—13 and the clasps 3. The inner members 12 of the pairs of tubular binding members are split longitudinally for a portion of their length as indicated in Figs. 2 and 4 of the drawings. This enables the said inner members to contract diametrically and gives them spring 90 action which facilitates the insertion of the inner members in the outer members and also increases the friction between them. After placing the binding members 12—13 through the openings in the sheets and binders, but a slight pressure or rap will cause them to hold by friction, completing the 100 binding process, a slight pressure also fastens the bound sheets to the movable cover at the clasp heads 4. When desired, the bound sheets are detached from the movable cover 1 by pulling and are ready to file away. When all the checks or leaves have been used, their stubs which are preserved in the binder 9, may, together with the said binder be detached from the cover and filed away for future reference and a 110 new binder with a new supply of checks or leaves then placed and fastened in the

cover by merely engaging the heads of the clasps 3 with the socket or flange of the tubular binding members 13. The said clasps 3 are permanently secured to the cover.

In Fig. 5 the binder is shown as a comparatively narrow strip 19, which makes a back and has flaps 20, 21 to catch the binding tubes on top and bottom of the sheets.

In Fig. 6, narrow strips 22 are shown on the top and bottom of the sheets to catch the binding tubes.

In Fig. 7 I show the form of book shown in Fig. 1, with its leaves and stubs intact and provided with a binder comprising a piece of flexible material forming a back 23, a flap 24 on the top of the sheets or leaves to catch the end of the binder tubes and a cover 25 to catch the lower ends of the binder tubes, the cap being broad enough to cover the top and bottom of the stubs, this binder corresponding with that shown in Fig. 1.

In Fig. 8, the binder 26 is shown as provided with a flexible extension 27 on the lower side, adapted to be folded back, over the top of the stubs, to keep out dust.

My improved binder may also be used on books of other forms.

While I have herein shown and described a preferred embodiment of my invention, I would have it understood that changes may be made in the form, proportion and construction of the several parts without departing from the spirit of my invention and within the scope of the appended claims.

In practice, banks and merchants will be furnished with sheets or checks having open-

ings to register with those of the binder. When the sheets or checks are secured in the binder by the binding tubes, they form a permanently bound book to be placed and secured in covers. After the sheets or checks have been used, the stubs remain in the binder, and form a book of stubs which may be readily removed from the covers and filed away.

I claim:—

1. In combination with a cover, a base secured to the cover and having a clasp stem, a binder, leaves arranged with one end or edge in the binder, said leaves and binder having coincident openings, and a pair of tubular binding members telescopically arranged, extending through said openings of the leaves and binder and being provided with heads bearing on opposite sides of the binder, one of said binding members having a socket or flange in its outer end for engagement by said clasp stem.

2. In combination with a book cover, a base secured to the cover and having a clasp stem, and a pair of tubular binding members telescopically arranged and provided at their outer ends with heads one of said binding members also having a socket or flange in its outer end for engagement for said clasp stem for the purpose set forth.

In testimony whereof I affix my signature in presence of two witnesses.

ROGER L. NAY.
